HAT IRONING MACHINE

William Joseph Byrne, Indianapolis, Ind.

Application August 24, 1931. Serial No. 558,978

11 Claims. (Cl. 223—28)

This invention relates to the art of hat pressing or ironing devices employing a hand operated, electrically heated iron and has for one of its objects the providing of a simple, effective, inexpensive means for detachably fixing a hat block on a driving member without damage to the block.

An object of the invention is to provide an improved head from which a hand iron may be supported and withdrawn for free use over and around a hat block without having to detach the iron from the head.

An object of the invention is to provide safety means to prevent damage to a hat should the operator forget to cut off the flow of current to the iron and leave the device in operation.

A further object of the invention is to provide means for retaining the iron on a hat to utilize the heat remaining in the iron after the current flow is interrupted.

A still further object of the invention is the particular combining of the various elements as set out in the accompanying claims to form an improved mechanism with better operation than found in the devices heretofore employed.

These and other objects will become apparent in the following description of the invention as shown in one particular form by the accompanying drawings, in which

Fig. 1 is a front view in perspective of a device embodying my invention;

Fig. 2, an opposite side elevation of the iron supporting and control head;

Fig. 3, a detail in top plan view of the iron attaching rod;

Fig. 4, a side elevation of a hat brim block on the driving spindle;

Fig. 5, a horizontal section on the line 5—5 in Fig. 4;

Fig. 6, an underside view in perspective of a hat crown block;

Fig. 7, a side view in perspective of the block driving spindle; and

Fig. 8, a top plan view of the entire device with the switch box removed.

Like characters of reference indicate like parts throughout the several views in the drawings.

I provide a motor 10 having a suitable reduction gearing between the armature shaft and a vertically disposed spindle 11, the gearing being enclosed in the housing 12 mounted directly upon one end of the motor. The details of construction of the motor unit with the reduction gearing form no part of my invention, and the unit may be obtained commercially.

The essential feature of the unit is that there be a slowly revolvable motor driven, vertical spindle. The motor may be mounted upon any base, here shown as the platform 13 supported by the three legs 14, 15, 16. A motor control switch 17 is fixed at one side of the motor.

I form a sleeve 18 to have an upper with a cup 19 and bore out the sleeve to permit it to be slipped over the spindle 11 concentrically and there fixed by the pin 20 to have a length of 65 the spindle to extend above the cup 19. The internal bore of the cup 19 is larger than that of the sleeve and somewhat eccentric of the spindle 11, Figs. 5 and 7.

With my device, standard hat blocks 21 and 22 may be employed. The crowning block 22, Fig. 6, comes with a central depending post 23 having a bore 24 therein. The diameter of the spindle 11 is made to permit the block to be placed thereover to have the bore 24 receive 75 the spindle 11 therein with a sliding fit. A plate 25 is formed with a central hole therethrough of the same diameter as that of the bore 24 and is secured to the underside of the post 23 to have the hole register with the bore 80 of the post. The diameter of the periphery of the plate 25 is made to be slightly less than the internal diameter of the cup 19 and the periphery is eccentric of the center hole through the plate.

A hat 26, Fig. 8, is forced down over the block 22 in the usual way after being cleaned and while still wet or damp. The block 22 with the hat thereon is then taken to the ironer and the post 23 placed down over the spindle 11 and 90 shifted rotatably to bring the plate 25 down into the cup 19. With the plate 25 within the cup, the block is given a quick twist to the right to cause the plate 25 to turn within the cup 19 about the spindle 11 and by reason of the eccentricity of both the internal wall of the cup 19 and the external edge of the plate 25, the edge of the plate will wedge tightly against the wall of the cup to such an extent that the block 22 can not be lifted vertically off the spindle. 100 Hence the hat 26 may be pulled off the block or shifted thereon without the danger of the block 22 being momentarily lifted from the spindle and then dropping out from the hat to fall on the operator's feet. Not only does this gripping 105 of the plate with the cup prevent accidental lifting of the block from the spindle, but it forms a driving connection whereby rotation of the spindle 11 by the motor 10 will correspondingly revolve the block 22 and the hat thereon. The 110

initial twist of the block 22 to fix the plate in the cup 19 may of course be in either direction depending upon the direction of rotation of the spindle, the twist being made so that the plate 5 tends to be held engaged rather than loosened upon resistance being applied to the block 22 upon its rotation. A quick twist of the block in the opposite direction will loosen and turn the plate 25 within the cup 19 to permit the 10 block being lifted off the spindle 11 when desired.

Referring to Fig. 4, when the block 21 is used for holding the hat to iron the brim, a plate 28 is made and secured to the underside of the 15 block. This plate is provided with a central body which is bored through to permit it being slipped over the spindle 11. The under side of the body has a boss 29 turned eccentrically to be of the same conformation as that of the 20 plate 25 whereby this boss may be entered within the cup 19, engaged and released, as above described in reference to the plate 25.

The means for holding and revolving the hat in the two positions for ironing having been 25 described, the means for supporting and controlling the iron will now be described.

A post 30 is fixed at the back and to one side of the motor 10 and has a collar 30' fixed thereon to hold a head 31 at a fixed elevation but 30 to permit the head to be freely revolved horizontally therearound. This head 31 is here shown as being hollow and has an arm 32 pivotally secured by one end at the rear of the head to permit the arm to project forwardly and be rocked up and down therewithin. The underside of the head is open and the arm 32 carries a weight 33 on its free end. A cord or cable 34 is fixed by one end to the arm 32 and is carried up within the head, over a revolvable spool 35 out through an opening in the head to have the other end fixed to a tube 36. This tube 36 is rockably attached to the head 31 near the rear end thereof here shown as being pivoted by an ear 37 on the same bolt 37' which passes 45 through the head and carries the arm 32. By this arrangement, the weighted arm 32 tends to drop down and pull the forward end of the tube 36 upwardly.

A rod 38 is telescoped within the tube 36 and 50 has a fitting 39 hinged to its forward end to engage with and be fixed to the heel of an ordinary electrically heated sad iron 40 whereby the iron is rockably attached to the rod 38 but rotation of the iron will cause a corresponding rotation of the rod. The forward end of the tube 36 is flared outwardly to have spaced apart upper and lower lips or flanges 41 and 42, between 55 which the fitting 39 may be pushed and held to hold the iron in a position fixed relative to the tube 36. The weight 33 is proportioned so that it will not quite balance the iron and the supporting rod and tube. A bar 45 is fixed to the head 31 in spaced relation thereto on the outer side of the tube 36 as a guide for the tube, and a latch 44 is provided on the head to swing 60 across the path of the tube 36 so that the iron 40 may be pushed back toward the tube 36 to be held by the end thereof and then raised to have the latch drop under the tube and hold it in an upper position.

A switch box 45' is fixed on the upper end of the post 30 and a cord 46 is carried from the box through a flexible arm 47 and to the usual plug 48 which is inserted at the rear of the iron 40. 75 The length of the cord 46 is relatively short for

a purpose hereinafter described. A switch control toggle arm 49 extends from the box 45' and may be rocked downwardly to be in the "on" position and upwardly to the "off" position. A lever 50 is pivoted to the rear side of the box 45' and extends around to in front of the box to be in the path of the arm 49. A second lever 51 is pivoted to the post 30 below the box 45 and a link pivotally interconnects the two levers whereby through the action of gravity, the lever 50 is normally in contact with the arm 49.

The upper end of the bar 45 is carried rearwardly and curved around concentrically with and spaced from the post 30 to be just under the rear end of the lower lever 51. A notch 52 is cut in the upper side of this bar extension to permit the lever 51 to enter therein.

In operating the invention after the block with its hat thereon has been fixed over the spindle 11, the motor 10 is set in operation to cause the block to revolve. Also, the switch arm 49 is pushed lower to cause current to flow and heat the iron 40. Pushing the arm 49 down rocks the lever 50 to lift the lever 51 from contact with the rear extension of the bar 45. The iron 40 is grasped by the handle by the operator, lifted to permit the latch 44 to be swung out of the way, and then lowered and pulled forwardly and held against the revolving hat on the block with the desired pressure. The iron may be moved forwardly or rearwardly, and down over the side of the crown as in Fig. 8. As the iron moves forwardly or rearwardly, the rod 38 slides accordingly within the tube 36 and as the iron is shifted across the hat toward 110 and away from the center of rotation, the head 31 is swung correspondingly about the post 30 as the rod 38 within the tube 36 may guide it.

Now should the operator be called away from the device before the hat has been dried and ironed out, he may allow the motor 10 to continue to run, but will push the arm 49 up to cut off the flow of current to the iron. Pushing up this arm allows the lever 50 to rock to let the lower lever 51 drop and rest on the rear extension of the bar 45. The iron 40 is moved over the hat to revolve the head to allow the lever 51 to drop into the notch 52 which action prevents further rotation of the head. Thus the iron remains in contact with the revolving hat and the residual heat left in the iron after stopping the current flow is utilized to further dry the hat while the operator is away without danger of scorching or burning the hat.

Should the operator leave the machine with the iron resting on the revolving hat and forget to raise the switch arm 49, the revolving block with the hat thereon will soon cause the iron to be shifted to the side whereupon the iron will fall down to the limit of travel of the tube 36 between the bar 45 and the head 31, below the hat, and this distance is such that it exceeds the length of the cord 46 between the box 45' and the iron 40 so that, as the iron drops below the hat, the plug 48 is jerked out of the iron and the current flow thus stopped.

When the crown of the hat has been dried and sufficiently pressed, it is pulled up off of the block 22, with the block being held down by the plate engaging in the cup as above described and the process repeated on the block 21 to work on the brim of the hat.

While I have here shown and described my invention in the form as now best known to me, it is obvious that structural changes may be

made without departing from the spirit of the invention, and I therefore do not desire to be limited to that precise form any more than may be required by the following claims.

5 I claim:

1. The combination of a revolvable spindle, a member adapted to be revolvably placed over the spindle, a cup on the spindle presented toward the member and having an eccentric bore, and an eccentric plate on the underside of the member adapted to be received within said cup and revolved therein to wedge against its wall to prevent withdrawal of the member from the spindle and to form a driving engagement therewith.

10 2. In an attachment for a hat ironing machine, a spindle, a hat block comprising a sleeve to be slipped over and secured to the spindle, the sleeve having an upper cupped end with a bore eccentric of the spindle, and a plate to be fixed to the under side of the hat block, the plate having a central hole to receive the spindle therethrough and an outer eccentric edge adapted to be received within the said cupped end.

15 3. In a hat machine, a revolvable spindle, a hat block, and means for detachably engaging the block with the spindle upon less than one complete rotation of the block to prevent withdrawal of the block therefrom, a horizontally revolvable head extended laterally of its axis of revolution, an iron, an iron support pivoted to the extension of the head to permit the iron to be raised and lowered vertically close beside the head, and a latch member carried by the 20 head near its axis of revolution for holding the iron in an upper position removed from said block, said support comprising an arm adjustable in length hinged to the head at one end and to the iron at the other end and means on the 25 arm to support the iron in a fixed position.

4. In a hat machine, a revolvable spindle, a hat block, and means for detachably engaging the block with the spindle upon less than one complete rotation of the block to prevent withdrawal of the block therefrom, a horizontally revolvable head extended laterally of its axis of revolution, an iron, an iron support pivoted to the extension of the head to permit the iron to be raised and lowered vertically close beside the head, and a latch member carried by the 45 head near its axis of revolution for holding the iron in an upper position removed from said block, said support comprising a tubular member pivoted to the head and a rod telescoping 50 with the tube, the iron being hinged to the rod.

5. In a hat machine, a revolvable spindle, a hat block, and means for detachably engaging the block with the spindle upon slight rotation of the block to prevent withdrawal of the block therefrom, a horizontally revolvable head, an iron, an iron support pivoted to the head to permit the iron to be raised and lowered vertically, and a latch member for holding the iron in an upper position removed from said block, said support comprising a tubular member pivoted 60 to the head and a rod telescoping with the tube, the iron being hinged to the rod, and means on the outer end of said tube to receive and support said iron in a fixed position.

6. In a hat machine, a revolvable spindle, a hat block, and means for detachably engaging

the block with the spindle upon slight rotation of the block to prevent withdrawal of the block therefrom, a horizontally revolvable head, an iron, an iron support pivoted to the head to permit the iron to be raised and lowered vertically, 80 and a latch member for holding the iron in an upper position removed from said block, a switch arm for controlling flow of current to said iron, and lever means controlled by movement of said switch arm adapted to intercept rotary movement of said head.

7. In a hat ironing machine, a head, a supporting post about which the head may revolve, a member pivoted to the head, an iron supporting means telescopically connected to the member to permit rotation of the iron about the member, and means on the member for receiving the iron and holding it against rotation.

8. In a hat ironing machine, a head, a supporting post about which the head may revolve, a member pivoted to the head, an iron telescopically connected to the outer end of the member to permit rotation of the iron about the member, and means on the member for receiving the iron and holding it against rotation, a switch 95 control arm above said head, a member on the head having a notch therein, and lever means between said arm and said notched member adapted to intercept said notch and prevent rotation of the head upon the arm being shifted 100 to an "off" position.

9. In a hat ironing machine, a block on which the hat to be ironed is placed, automatic means for revolving the block, a rotatably movable head, an iron carried by the head and moved 110 manually over the hat on the block, switch means for controlling flow of current to the iron and means for arresting the movement of the head and for retaining the iron in contact with the hat on the block after the operator 115 has turned the switch to stop the flow of current to the iron and has released manual control of the iron comprising a switch arm, a locking lever, means by moving the switch arm to close the circuit, for lowering the locking 120 lever and a member having a notch which is entered by the lever upon the appropriate swinging of the head.

10. In a hat machine, a hat block, a circular plate moving with the block and having a bore 125 eccentric to the periphery of the plate, a revolvable spindle seated in the bore, and a cup fixed to the spindle, said cup having a bore eccentric to the spindle and receiving the plate in said last mentioned bore.

11. In a hat ironing machine, a block on which a hat to be ironed is placed, motor means for revolving the block, an electrically heated iron, a switch plug in the circuit of the iron, means comprising a horizontally swinging head and a telescoping arm pivoted to the head and partially balanced for movably supporting the iron in contact with the hat while the iron is manually directed and whereby the iron when manually released moves to an unsupported 140 position and falls by gravity, and a cord connecting the iron with the plug to remove the plug and break the circuit by the fall of the iron.

WILLIAM JOSEPH BYRNE. 145
